SHEET CONVEYER FOR FOLDING MACHINES.

No. 322,344.

Patented July 14, 1885.

UNITED STATES PATENT OFFICE.

RICHARD T. BROWN, OF ERIE, PENNSYLVANIA, ASSIGNOR TO THE BROWN FOLDING MACHINE COMPANY, OF SAME PLACE.

SHEET-CONVEYER FOR FOLDING-MACHINES.

SPECIFICATION forming part of Letters Patent No. 322,344, dated July 14, 1885.

Application filed August 4, 1884. (No model.)

To all whom it may concern:

Be it known that I, RICHARD T. BROWN, a citizen of the United States, residing at Erie, in the county of Erie and State of Pennsylvania, have invented certain new and useful Improvements in Sheet-Conveyers for Connecting a Printing-Press with a Folding-Machine; and I do hereby declare the following to be a full, clear, and exact description of the invention, such as will enable others skilled in the art to which it appertains to make and use the same.

This invention relates to sheet-conveying appliances for connecting paper-folding machines with printing-presses, so that the printed sheets will be conveyed from the press to the folder.

The objects, purposes, and scope of this invention will be fully set forth in the following description, and pointed out in the claims.

The invention is illustrated in the accompanying drawings, as follows: Figure 1 is a top or plan view showing a fragment of the press A, the folder B, and my improved conveyer C, adjusted between the press and the folder. Fig. 2 is a side elevation showing a fragment of the press A, the folder B, and the conveyer C, adjusted between the press and the folder. Fig. 3 is a vertical longitudinal section through the conveyer on the line x x in Fig. 1, the scale being enlarged and the figure shortened by breaking out parts.

The conveyer consists of a board or table, C, upon which are adjusted two sets of conveying-rollers, E f and E' f', which convey the sheet along the board or table from the press to the folder, together with means for operating said rollers, and also means for keeping the sheet in place upon the table. The conveyer is so constructed that it can be adjusted, as shown, between the press and the folder, or quickly and easily removed from that position when not wanted. When in position, it is operated from a belt-pulley, B', on the folder by a belt, C'. When put in position for use, no adjustment is required except to put it in proper place and adjust the belt C'.

The construction, as illustrated in the drawings, is as follows: A represents the press; a, the delivery-tapes of the press; B, the folder;

b, the tapes of the folder, and C the conveyer-table. c² c², &c., are notches at the upper end of the conveyer-table, which span or embrace the delivery-tape rollers of the press. c³ are like notches at the lower end of the conveyer-table, which span or embrace the tape-rollers of the folder. c⁴ are pins in the foot of the conveyer-table, which enter holes in the table of the folder and serve to brace or hold the conveyer in place. c and c' are slots through the table of the conveyer, for the conveying-rollers E E' to operate through. D and D' are the shafts of the conveyer-rollers E and E', respectively. F and F' are the shafts of the conveyer-rollers f and f', respectively. H and H' are the hangers or brackets of the shafts D and D' and F and F', respectively. G and G' are bridges which support guides g, which lie near the conveyer-table and keep the sheets in place upon the table while passing along it.

The conveying-roller shafts D and D' are driven as follows: The belt C' passes from the pulley B' to a pulley, C', on the shaft D. These pulleys are so proportioned that the speed of the conveyer-rollers E on the shaft D will be the same as the speed at which the sheet leaves the delivery-tapes a of the press. The shaft D', which carries the conveyer-rollers E', is driven from the shaft D by the pulleys d and d' and belt d'. The pulleys d and d' are so proportioned that the rollers E' will move slower than the rollers E. This may not always be required; but the object of it is to slow down the speed of the sheet so it will enter the folder at less speed than it left the press. In passing across the space between the rollers E to E' the sheets will gather or ruffle up by reason of this change of speed; but the guides g will keep it in place perfectly. The rollers f and f' are operated by friction from the rollers E E', upon which they ride.

The slots c, in which the rollers E are adjusted, are made long, so that the shaft D' may be placed at various distances from the shaft D, if desired, so as to adjust the conveyer to different-sized sheets.

Where the space between the two machines is very short, only one set of conveyer-rolls

may be used, and if the space is too great for two sets of conveyer-rolls to convey the sheet properly other sets may be added.

What I claim as new is—

- 5 1. In a sheet-conveyer for connecting a printing-press with a folding-machine, the combination, substantially as described, of a table which spans the space between said machines, and two sets of conveyer-rolls, between which the sheets pass, connected with said table, and arranged relatively, as set forth, the second of which sets is operated at a slower speed than the first, for the purposes mentioned.

2. In a sheet-conveyer for connecting a 15 printing-press with a folding-machine, the combination, substantially as described, of the table C, having notches and slots, as described, the shafts D and D' with rollers E and E', the shafts F and F' with the rollers f 20 and f', and the bridges G and G', holding the guides g g g, &c.

In testimony whereof I affix my signature in presence of two witnesses.

RICHARD T. BROWN.
